UNITED STATES PATENT OFFICE.

DAVID H. STROUD, OF JENKINTOWN, PENNSYLVANIA.

DESIGN FOR A RUG.

Application filed July 1, 1927. Serial No. 22,634. Term of patent 7 years.

To all whom it may concern:

Be it known that I, DAVID H. STROUD, a citizen of the United States, residing in Jenkintown, in the county of Montgomery and State of Pennsylvania, have invented a new, original, and ornamental Design for Rugs, of which the following is a specification, reference being had to the accompanying drawing, forming part thereof, in which the representative portion indicates one-half of the rug, the other being a repetition thereof.

The figure is a face view of a rug showing my new design.

I claim:

The ornamental design for a rug, as shown and described.

DAVID H. STROUD.
